PAINT APPLICATOR

Carl T. Olson and Charles F. Eckert, Belle Vernon, Pa., assignors of twenty-five percent to Frank Giuliano, Belle Vernon, Pa.

Filed Oct. 18, 1961, Ser. No. 145,898
6 Claims. (Cl. 15—522)

This invention relates to paint applicators of the roller type including its own supply of paint for distribution to the roller for spreading thereby on walls, ceilings and other flat surfaces.

The primary object of this invention, is to provide a paint rolling apparatus containing its own supply of paint for even distribution on the roller for painting remotely accessible surfaces while avoiding the inconvenience of frequently dipping the roller in a pan of paint.

It is a further object of this invention to provide means for collecting any excess paint on the roller for return to the paint supply carried within the applicator itself which applicator nevertheless will not permit spillage of paint therefrom when not in an upward paint spreading position.

In accordance with the foregoing objects, the applicator involves an elongated handle, rotatably mounting at one end thereof a paint spreading roller, in contact with a paint distributing roller to which paint is supplied from a reservoir chamber located within the handle portion of the applicator which handle includes its own manual actuatable pump for filling the distributing roller with paint when desired. The handle is hollow and of considerable length so that the user may reach remotely accessible surfaces and also so that the handle may constitute a sizable paint reservoir chamber requiring infrequent loading. A funnel-shaped paint collecting shroud encloses the paint distributing roller and thereby channels excess paint on the spreading roller back into the reservoir chamber in the handle through a one-way valve which prevents the flow of paint out of the reservoir chamber and thereby prevents spillage.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a perspective view of the applicator unit representing the invention of this application.

FIGURE 2 is a longitudinal sectional view of the applicator along the plane indicated by the section line 2—2 in FIGURE 1.

FIGURE 3 is a side sectional view of the top half of the applicator through a plane indicated by the section line 3—3 in FIGURE 2.

FIGURE 4 is a view taken through the plane indicated by the section line 4—4 in FIGURE 2.

FIGURE 5 is a longitudinal sectional view of the lower part of the applicator with the pump plunger shown in an intermediate position.

Referring first to FIGURE 1, there is shown therein the applicator generally designated by the reference numeral 10 which includes an elongated handle portion 12 having a funnel-shaped shroud 14 connected thereto at its upper end exposing a paint spreading roller 16 rotatably mounted on bracket 18 also secured to the top end of the handle 12.

Referring now to FIGURE 2, bracket 18 has secured thereto a spindle 20 on which the roller 16 is rotatably mounted and also fixedly secured to the bracket 18 is a hollow axle 22 sealed at one end by part 24 and connected at its other end by fitting 26 to a conduit 28 extending beneath bracket 18 and down along the handle

12. The hollow axle 22 has a plurality of apertures 30 for passage of paint therethrough into a roller 32 which is hollow and is rotatably mounted on the axle 22, said roller 32 constituting a paint distributing roller having apertures 34 therein and being in contact with the paint spreading roller 16 as more clearly seen in FIGURE 3.

As seen in FIGURE 2, the handle portion 12 of the applicator has a paint reservoir chamber 36 which may be loaded with paint by pouring paint into the top of the funnel-shaped shroud 14, the paint then entering inlet 38 and openings 40 into the chamber 36, the ball valve 42 preventing any flow of paint out of the chamber 36 because of movement of the ball valve 42 to close the inlet 38. At the bottom of the handle portion 12 is a pump chamber 44 separated from the paint reservoir chamber 36 by a spring biased one-way valve 46 which will open in response to suction created within chamber 44 to admit paint from chamber 36 into chamber 44. The chamber 44 is connected to the conduit 28 by means of one-way ball valve 46' located within fitting 48 for connecting the pump chamber 44 to the conduit 28 in one direction for supplying paint to the distributing roller 32 via hollow axle 22.

In order to pump the paint into the distributing roller 32 when additional paint is desired for the roller 16, the pump chamber 44 is provided with a pump piston 50 which may be actuated by a plunger 52 against the bias of spring 54. As seen in FIGURE 5, the plunger 52 and piston 50 are in an intermediate position and moving 25 in the direction indicated by the arrow 56 shown in solid lines, so that paint trapped between the piston 50 and valve 46 is forced past one-way valve 46' into conduit 28 for supply to the paint distributing roller 32. When the piston 50 is being retracted by the spring in the direction of arrow 58 shown in dotted lines in FIGURE 5, suction 30 is created in the chamber 44 above the piston 50 thereby 35 opening valve 46 against its spring bias as shown in dotted lines in FIGURE 5, to admit paint from the chamber 36 into pump chamber 44 while one-way valve 46' 40 prevents egress of paint from chamber 44 as it is being charged with paint from chamber 36 in preparation for a following pump stroke actuation of the plunger 52.

As previously indicated, one-way valve 42 prevents the flow of paint from chamber 36 out of inlet 38 so that when the applicator is held in a downward position, opposite to the position as shown in FIGURE 1, no paint will spill out of chamber 36. It may however be desirable at times to selectively permit paint to flow out of chamber 36 into the funnel-shaped shroud 14, as for example when it is desired to paint a floor, in which case the valve 42 may be held in its open position by means of a finger 60 secured to a pin or shaft 62 pivotally mounted in the handle and connected to a lever or arm 55 64 which is connected by link 66, as more clearly seen in FIGURE 1, to a slide member or ring 68 slidably mounted on the outside of the handle portion 12 and actuatable against the bias of spring 70.

From the foregoing description, operation and use of the applicator is clearly apparent. It is also apparent, that the applicator may easily be cleaned by removal of the paint roller, draining the paint out of the chamber 36 by holding the valve 42 open through movement of slide 68, pouring paint remover or thinner into the chamber 36 and finally pumping it through the applicator with its pumping mechanism.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and

equivalents may be resorted to, falling within the scope of the invention as claimed.

What is claimed as new is as follows:

1. A paint applicator comprising a hollow handle, pump means located at one end of said handle, paint collecting means mounted at an opposite end of said handle and reservoir means disposed within said handle and intermediate the ends thereof, paint spreading means and distributing means mounted at said opposite end of said handle and supply means responsive to actuation of said pump means for supplying paint from said reservoir means to said distributing means, said reservoir means including a releasable one-way valve connecting the collecting means and the reservoir means for permitting flow of paint from said collecting means to said reservoir means, and means for releasing the valve comprising a ring slidable on the handle and operatively connected to said valve.

2. The applicator as defined in claim 1, wherein said supply means includes a hollow axle mounting said distributing means, conduit means connecting said pump means to said axle, said axle having apertures therein for the passage of paint therethrough to the distributing means.

3. The applicator as defined in claim 1, wherein said pump means includes a plunger-actuated piston, slidable within a pump chamber formed at said one end of the handle, and oppositely acting one-way valve means connecting said pump chamber with said supply means and reservoir means respectively.

4. A paint applicator comprising a hollow handle, pump means located at one end of said handle, paint collecting means mounted at an opposite end of said handle and reservoir means disposed within said handle and intermediate the ends thereof, paint spreading means and distributing means mounted at said opposite end of said handle and supply means responsive to actuation of said pump means for supplying paint from said reservoir means to said distributing means, said reservoir means including a releasable one-way valve connecting the collecting means and the reservoir means for permitting flow of paint from said collecting means to said reservoir means, said supply means including a hollow axle mounting said distributing means, conduit means connecting said pump means to said axle, said axle having apertures therein for the passage of paint therethrough to the distributing means, and means for releasing the valve comprising a ring slidable on the handle and operatively connected to said valve.

5. A paint applicator comprising a hollow handle, pump means located at one end of said handle, paint collecting means mounted at an opposite end of said handle and reservoir means disposed within said handle and intermediate the ends thereof, paint spreading means and distributing means mounted at said opposite end of said handle and supply means responsive to actuation of said

pump means for supplying paint from said reservoir means to said distributing means, said reservoir means including a releasable one-way valve connecting the collecting means and the reservoir means for permitting flow of paint from said collecting means to said reservoir means, said supply means including a hollow axle mounting said distributing means, conduit means connecting said pump means to said axle, said axle having apertures therein for the passage of paint therethrough to the distributing means, said pump means including a plunger-actuated piston, slidable within a pump chamber formed at said one end of the handle, oppositely acting one-way valve means connecting said pump chamber with said supply means and reservoir means respectively, and means for manually releasing the first-named valve, the last-named means including a ring slidably mounted on the handle and operatively connected to said first-named valve.

6. A paint applicator comprising an elongated hollow handle rotatably mounting at one end, a paint spreading roller and fixedly mounting parallel thereto, a hollow axle having apertures therein, a paint distributing roller having apertures therein rotatably mounted on said hollow axle and contacting said paint spreading roller, a funnel-shaped shroud partially enclosing said distributing roller connected to said hollow handle adjacent said one end thereof, a pump chamber located within said hollow handle at its other end, a reservoir chamber located within said handle intermediate the ends thereof, a conduit connecting said pump chamber to one end of said hollow axle, oppositely acting one-way valves connecting said pump chamber to the conduit and reservoir chamber respectively, a one-way spillage valve located in said reservoir chamber at one end thereof adjacent said one end of the handle and connecting the collecting chamber with the reservoir chamber and selectively operable means for holding said spillage valve in open position, the last-named means including a shaft journaled in the reservoir chamber, an arm on the shaft, a ring slidable on the reservoir chamber, a link operatively connecting said ring to the arm, and a finger on the shaft engageable with the spillage valve for opening same.
